LAST

Austin Nacefski, Nashua, N. H., assignor to J. F. McElwain Co., Suffolk County, Mass., a corporation of Massachusetts

Application February 1, 1936, Serial No. 61,902

6 Claims. (Cl. 12—133)

The operation of securing a heel to a shoe usually is performed in a heelng machine which drives simultaneously all of the nails required for this purpose. At the time this operation is performed the shoe customarily is on the last on which it was made. The heelng machine includes gaging devices for positioning the shoe heel properly with reference to the nail plate and also is equipped with a jack post mechanism carrying a jack pin for entering the thimble on the last and assisting in centering the heel end of the shoe with reference to the nail plate and the other nail driving instrumentalities. Usually, also, some additional positioning means is provided for engaging the counter portion of the shoe to aid in this centering operation. The position of the shoe during this heel attaching operation is, however, chiefly controlled by the operator. He moves the shoe in a horizontal plane into a position, largely determined by his eye, which he regards as correct, and then operates the treadle which sets into motion the nail driving instrumentalities.

The position of a heel with reference to the median plane of a shoe varies considerably in different styles of shoes. In a shoe made on a so-called "straight" last, the heel may line up with the shoe, or the angle of divergence between the two may not be great, but in a very high percentage of shoes, particularly men's shoes, and more especially those made on "crooked" lasts or those having a decided "swing", the center line of the heel makes a relatively large angle with the center line of the shoe. This angle is determined chiefly by the operator and it is not an easy matter for him to position every shoe of a given size and style in exactly the same relationship to the nailing mechanism. Naturally the results produced are affected by the care and skill exercised, by fatigue, and other human factors.

The present invention aims to facilitate the heelng operation with a view to eliminating, or at least substantially reducing, the variations due to the causes above described. It is an important object of the invention to devise means for so assisting the operator in positioning shoes for the attachment of their heels that much of the care, skill and judgment required of him will be eliminated, and the heels on successive shoes of any given size and style consequently will be positioned with a high degree of uniformity.

The nature of the invention will be readily understood from the following description when read in connection with the accompanying draw-

ings, and the novel features will be particularly pointed out in the appended claims.

In the drawings,

Figure 1 is a perspective view of the cone portion of a last equipped with a guiding element embodying a feature of this invention;

Fig. 2 is a side elevation, with parts in vertical section, illustrating means for positioning a shoe in a heelng machine in accordance with this invention;

Figs. 3, 4 and 5 are front, side and bottom views, respectively, of a jack post mechanism equipped with a positioning or guiding element embodying a feature of this invention;

Fig. 6 is a side elevation showing the invention applied to another type of jack post mechanism;

Fig. 7 is a rear elevation of the jack post shown in Fig. 6; and

Figs. 8 and 9 are plan views, partly in section, illustrating other embodiments of the invention.

Referring first to Figs. 2 to 4, inclusive, the nail plate of a heelng machine of a common commercial type is shown at 2, and the jack post mechanism is indicated in general at 3. It comprises a body member having a dove-tail projection to fit into a corresponding groove in the support 4, and also includes a slide 5 in which a jack pin 6 is secured. This arrangement provides for both a backward and forward movement of the shoe, together with the pin 6 and slide 5, to position the shoe for the heelng operation, and also for the swinging movement of the shoe in a horizontal plane, as above described. The heel 7 is positioned by any suitable gaging devices with which the heelng machine customarily is equipped, so that its location with reference to the nail plate 2 and the other nail driving instrumentalities is predetermined and substantially fixed, although adjustable.

According to the present invention additional devices are provided to cooperate with each other in determining the angular position of the last in a horizontal plane, one of these devices being mounted in the machine and the other carried by the last. In the particular arrangement illustrated in Figs. 1 and 2 the forward end of the upper portion of the heel part of the last 8 is notched or cut away to receive a guide plate 10. Preferably this plate is made of angular form in order to give added strength and to provide increased area for receiving the screws by which it is secured to the last. The guiding or positioning portion of this plate, however, consists of the upright part of it, provided with a broad, flat, laterally disposed face extending at approximate-

ly right angles to the median plane of the last. In other respects this last may be of any suitable form, the particular construction shown having the usual hard fiber reinforcing plate 12 and the customary thimble 13.

The positioning element provided in the machine to cooperate with the part 10 consists of a plate 14, secured to the front vertical face of the jack post body 3 by means of screws 15. Preferably the lower portion of this plate is thickened and its rearward surface is bevelled, as shown at 16, Fig. 4, so as to provide a straight lower edge projecting somewhat behind the adjacent portions of the plate.

In using this invention, the heel 7 is positioned in the machine in the usual manner, and the last is slipped on to the jack post mechanism with the pin 6 inserted in the thimble 13. At this time the slide is pushed back away from the plate 14, but after the last has been placed in the relationship just described, it is then pulled forward, carrying the slide 5 and jack pin 6 with it, until the upright face of the plate 10 strikes the rearward edge of the stationary positioning plate 14. This contact with the parts 10 and 14 stops any further forward movement of the shoe, but if the plate 10 does not strike the member 14 in such a manner that the entire edge of the latter is in engagement with the former, then the forward pull on the shoe will tend to swing the shoe automatically until such engagement is produced. This swing of the shoe will take place around the axis of the pin 6, and the adjustment of the parts should be such that when the members 10 and 14 are in full engagement with each other, the heel will be centered properly with reference to the nail plate 2. It will be evident that the full engagement of the parts 10 and 14 with each other can occur only when the shoe is in a predetermined angular position in a horizontal plane. In other words, these parts determine this angular position in said plane. They also cooperate with the pin 6 to position the shoe correctly with reference to the nailing instrumentalities and the devices that position the heel 7.

Care should, of course, be taken to accurately position the last thimble 13 with reference to the shoe shaping surfaces of the last and to locate the plate 10 accurately with reference to said surfaces and the thimble 13. These results can, however, be readily produced in a line of lasts designed for the manufacture of a given style and size of shoe. If these operations are accurately performed during the manufacture of the lasts, then the arrangement above described greatly reduces the care, skill and judgment required in positioning the shoes in the heelng machine in order to be sure that the heels on the entire line of shoes of any given style or size are correctly located.

As above stated, it frequently happens that the center line of the heel makes a considerable angle with the median line of the last. The desired departures in the alinement of the parts may be made entirely by suitable changes in the position of the heel gaging devices, but this is not always possible or convenient, and in order to hold the shoe in different angular relationships to the nail plate or the heel, the plate 10 may be located in different angular relationships to the longitudinal median plane of the last. Or the same result may be obtained somewhat more conveniently by making either of the members 10 or 14 thicker at one side than the other. Such an arrangement is illustrated in Fig. 8 in which the

part 18 corresponds to the plate 10 and is made wedge-shaped, or thicker at one edge than the other, so that when it is in full engagement with the edge of the plate 14, it throws the median plane of the last 8 into a divergent position with reference to a vertical plane at right angles to the plate 14.

Another embodiment of the invention is illustrated in Fig. 9 in which the cooperating positioning members, instead of having straight or flat abutting surfaces, are made of angular formation. As shown in this figure the plate 10 has been replaced with a V-shaped plate 20 designed to fit into a complementary V-shaped notch 21 in the fixture 14', the latter member corresponding functionally to the fixture 14. This angular shape of the cooperating surfaces 20 and 21 is of assistance in centering the guiding element on the plate properly in the stationary fixture or guiding member secured to the machine, and thus correctly locating the shoe.

In that type of heelng machine in which the shoe is supported in an inverted position during the heelng operation, the same guiding members 10 and 14 may be used, as illustrated in Fig. 6. In this arrangement the plate 10 is secured to the last exactly as in the construction shown in Figs. 1 and 2. The jack post structure, however, is of a slightly different form, including a body member 22 having a concave upper surface to receive a rocking and sliding block 23 to which the jack pin 24 is secured. This is a jack post mechanism in common commercial use. The positioning plate or fixture 14 is secured to the member 22 in essentially the same relationship as in the construction illustrated in Fig. 2 where it will be engaged by the plate 10 on the last when the shoe is moved forward to position it for the heelng operation. It will be understood that in this type of heelng machine the nail plate and the heel positioning devices are located above the shoe, and the nails are driven downwardly through the heel instead of upwardly, as in the construction previously described. The shoe positioning operations, however, are performed in the same manner in this machine as in that shown in Fig. 2.

While I have herein shown and described typical embodiments of my invention, it will be understood that the invention may be embodied in other forms without departing from the spirit or scope thereof.

Having thus described my invention, what I desire to claim as new is:

1. A shoe last having a thimble to receive a jack pin, a lateral surface of the upper portion of the heel part of the last being provided with a horizontally extending recess, said recess having walls located at an angle to each other, and a metal plate secured to said last and having surfaces fitting against said walls of said recess.

2. A shoe last having a thimble to receive a jack pin, a lateral surface of the upper portion of the heel part of the last being provided with a horizontally extending recess, said recess having walls located at an angle to each other, an angular metal plate located in said recess and having an approximately horizontal flange fitting against one of said walls and an approximately vertical flange fitting against the other, and means securing said metal plate to the heel part of the last.

3. A shoe last having a thimble to receive a jack pin, a lateral surface of the upper portion of the heel part of the last being provided with a horizontally extending recess in the forward end

of the upper part of the heel portion of said last, and a flanged metal plate mounted in said recess and secured to the heel part of the last.

4. A shoe last having a thimble to receive a jack pin, and a positioning element secured to the upper portion of the heel part of said last and provided with a laterally directed V-shaped guiding surface.

5. A shoe last having a thimble to receive a jack pin, and a positioning element secured to the upper portion of the heel part of said last and pro-

vided with a laterally directed V-shaped guiding surface, the apex of said surface being located at the forward end of said heel part of the last.

6. A shoe last having a thimble to receive a jack pin, and a positioning element secured to the upper forward end of the heel part of said last and having an approximately upright positioning surface at the front thereof extending diagonally with reference to the longitudinal median plane of the last toward one side face of the last. 10

AUSTIN NACESKI.
